UNITED STATES PATENT OFFICE.

GEORGE W. GILMORE, OF WEBSTER, PENNSYLVANIA.

IMPROVEMENT IN PISTONS OR PLUNGERS FOR FORCE-PUMPS.

Specification forming part of Letters Patent No. 171,475, dated December 28, 1875; application filed April 28, 1875.

To all whom it may concern:

Be it known that I, GEORGE W. GILMORE, of Webster, Westmoreland county, State of Pennsylvania, have invented an Improved Piston or Plunger for Force-Pumps, of which the following is a specification:

The object of my invention is to cause the fluid to be discharged from the pump with greater force and velocity than can be done with pistons of the ordinary construction, and this to be done by the elasticity of a body of air in the piston acting on the column of water in the pump-barrel when the piston is driven downward.

The invention consists in making the piston with a hollow body, having air-inlets at the top, and an opening at the bottom, through which the air in the piston presses on the water in the barrel, when the piston is driven downward. The air-inlets and the opening in the bottom of the piston are alternately closed and opened by valves, which are operated by the reciprocation of the piston, so that when the piston is lifted the air-inlets are opened, and the opening in the bottom is closed, and water is prevented from entering the chamber; but when the piston is forced down the air-inlets are closed, and the opening in the bottom is opened, which permits the air in the chamber to press upon the fluid.

Figure 1 is a longitudinal section of my improved piston. Fig. 2 is an end view, showing the bottom of the piston; and Fig. 3 is also an end view, showing the top of the piston separate from it.

The following is a more particular description of said drawings which are hereby made a part of this specification, letters of reference being the same in all the figures.

A is the piston, which is hollow, and forms the air-chamber F. b is the opening in the bottom of the piston, through which the air in the chamber E presses on the water in the

barrel when the piston is driven downward. a a a are the air-inlets. G is a valve-rod guide, formed by a small bar crossing the opening b, and having a hole in the center g. H is also a guide-hole in the top or head of the piston, Fig. 3. D is the valve-rod, passing through the whole length of the air-chamber F, and retained in place by the guides G, g, and H. C and C' are two valves fast on the rod D, and at such points that when one is open the other will be closed. B is the piston-rod by which the piston is moved in the pump-barrel. The opening b is a hole in bottom of the piston about one-third ($\frac{1}{3}$) less in diameter than the air-chamber F, so as to form a valve-seat for the valve C, and the inlet is formed by several small holes surrounding the guide-hole H.

When the piston A is drawn up in the pump-barrel, the valve C closes the opening b, and the inlets are uncovered, and the chamber F becomes filled with air. On the downward movement of the piston-valve C' closes and C opens, and the air in the chamber E is caused to press on the top of the column of water in the barrel, and its elasticity gives greater force to the expulsion of the water from the pump than would be obtained by the pressure of the piston alone.

What I claim, and desire Letters Patent for, is—

A piston for force-pumps having the air-chamber F, air-inlets a a, openings b, and provided with the valves C C', which alternately open and close the said openings by the reciprocation of the piston, substantially as and for the purpose hereinbefore described and set forth.

GEORGE W. GILMORE.
